[57] CLAIM

The ornamental design for an orthopaedic clamp, as shown and described.

DESCRIPTION

FIG. 1 is a perspective view of an orthopaedic clamp. The broken line showing of the posts is for illustrative purposes only and forms no part of the claimed design;

FIG. 2 is a side elevational view thereof;

FIG. 3 is a side elevational view thereof of the side opposite the side shown in FIG. 2;

FIG. 4 is an end view thereof;

FIG. 5 is an end view thereof of the end opposite the end shown in FIG. 4;

FIG. 6 is a bottom plan view thereof; and,

FIG. 7 is a top plan view thereof.
